UNITED STATES PATENT OFFICE

127,593

DESIGN FOR A REFLECTOR

Albert Shuman, New York, N. Y.

Application September 6, 1939, Serial No. 87,061

Term of patent 7 years

To all whom it may concern:

Be it known that Albert Shuman, a citizen of the United States and resident of New York, in the county of New York and State of New York, has invented a new, original, and ornamental Design for Reflectors, of which the following is a specification, reference being had to the accompanying drawing, forming part thereof, in which—

Figure 1 is a perspective view of the reflector showing my new design, it being understood that the same ornamentation that has been partially illustrated extends over the remaining portions in the same relation;

Figure 2 is a top or edge view of the reflector as positioned in Figure 1; and

Figure 3 is a fragmentary cross sectional view of a portion of the reflector along the line 3—3 of Figure 1.

The design is characterized by a reflector of the form illustrated, the surface of which is provided with embossings positioned as shown, the embossings being deepest along the longitudinal edges of the reflector, decreasing in depth toward the longitudinal center, dying out before the longitudinal center is reached, and leaving the parallel unembossed areas on each side of said longitudinal center.

I claim:

The ornamental design for a reflector, substantially as shown and described.

ALBERT SHUMAN.
